UNITED STATES PATENT OFFICE.

WILLIAM A. GIBSON, OF PEORIA, ILLINOIS, ASSIGNOR TO WILLIAM E. HEARST, OF PEORIA, ILLINOIS.

FEED-WATER HEATER.

1,259,615.

Specification of Letters Patent. Patented Mar. 19, 1918.

Application filed July 30, 1914, Serial No. 854,019. Renewed August 17, 1917. Serial No. 186,823.

To all whom it may concern:

Be it known that I, WILLIAM A. GIBSON, a citizen of the United States, residing at Peoria, in the county of Peoria and State 5 of Illinois, have invented certain new and useful Improvements in Feed-Water Heaters, of which the following is a specification.

This invention relates to improvements in 10 feed water heaters for boilers, in which the water to be supplied to the boiler is passed in contact with steam heating elements for raising the temperature of the water before its admission to the boiler.

15 The object of my invention is to provide a heater of simple construction in which the steam, after passage through the steam heating elements, is exhausted directly into the water previous to its introduction into the 20 heater, thereby preventing waste of steam and also utilizing all the heating properties of the steam to raise the temperature of the water.

A further object is the introduction of 25 steam into the water duct in such a manner that it will tend to force the water through the heater.

In the accompanying drawings which 30 illustrate my invention Figure 1 is a side view of the heater, a portion thereof being broken out of the center to allow an enlarged view to be shown, a portion of the water feed pipe also being broken away at the point where the steam from the heater 35 is delivered thereto so as to show the structure for introducing the steam to the water duct; Fig. 2 is a vertical longitudinal sectional view through the heater shown in Fig. 1; and Fig. 3 is a partial view of a locomotive showing the manner of applying my 40 heater thereto.

In the drawings 1 and 2 are end fittings which are connected and spaced apart by means of the tube 3, secured to said fittings. 45 Extending entirely through the fittings 1 and 2 and the tube 3 is a tube 4 which is of somewhat less diameter than the tube 3 so as to provide a narrow annular passage way 5, for water, between the tubes 3 and 4.

50 This tube 4 is swaged or expanded at each end so as to provide a tight joint with the fitting 1 and a tight joint with the plate 6 which is bolted to the fitting 2 and forms a closure for the end of said fitting. Extend-

ing lengthwise within the tube 4 and placed 55 at the top thereof, is the tube 8 which is of considerably smaller diameter than the tube 4 so as to allow a large space between the tubes 4 and 8 for the passage and expansion of steam as hereinafter explained. The tube 60 8 at one end extends through and is secured to the head 9, which said head is bolted to the fitting 1 and forms a closure for the tube 4. The other end of the tube 4 is closed by means of the head 11 which is secured in 65 contact with the plate 6 by means of the bolts 7 which pass through the head 11 and the plate 6. The intermediate plate 6 is provided at one end of the heater to facilitate replacement of the tube 4. As is apparent, 70 when this tube 4 is to be replaced the swaged end of the tube 4, which engages the end fitting 1, is turned in by means of a chisel or otherwise so as to be released from the fitting 1 and the removal of plate 6 will 75 then withdraw the tube 4 from the heater.

The tube 8 terminates a short distance from the head 11 so as to provide an outlet therefrom into the larger tube 4 and this 80 said end of the tube 8 is supported by means of a stem 12 which is secured to the head 11 and engages the inner surface of the tube 8. The tube 8 has a small opening 10 in the bottom thereof adjacent the head 9 for discharging the water from the pipe 8 which 85 results from the condensation of steam therein.

13 (in Fig. 3) represents an injector or pump which is commonly used to force water into the boiler and the water feed pipe 14 90 therefrom is connected to the under side of the fitting 1 so as to communicate with the interior thereof and there is a pipe 15 connected to the fitting 2 at the bottom thereof which communicates through the 95 check valve 24 with the boiler so that the water supplied by the injector 13 passes through the pipe 14 into the fitting 1 and is then passed in a narrow stream through the annular opening 5 to the interior of the fitting 2, thence through the pipe 15 into the boiler.

A pipe 16 is connected to the steam dome 17 of the boiler and is connected with the protruding end of the pipe 8 to supply steam 100 to the heater, and the tube 18 is connected with the head 9 to provide an outlet from the tube 4 of the heater and this pipe is con-

nected through the check valve 23 and T 20 with the feed water pipe 14 at a point just ahead of its connection with the heater.

This T 20 is made with a contracted nozzle 19 through which the water is forced in a jet and the nozzle is surrounded by the steam chamber 21 which communicates with the pipe 14 through the annular passage way around the delivery end of the nozzle so that the steam is introduced into the water at this point.

Assuming that the injector 13 is forcing water through the heater into the boiler, the valve 22 being opened steam will enter the tube 8 and pass from the end of said tube into the tube 4, in which it is allowed to expand. The tube 4 presents a large surface to the water within the heater and by reason of the tube 8 being located within the tube 4 any heat from the tube 8 tends to raise the temperature of the steam within the tube 4, which acts upon the water in the heater and there is therefore no heat wasted in the passage of the steam through the heater. The exhausted steam from the heater passes through the pipe 18 into the chamber 21 of the T 20 and is forced into the water within the pipe 14 as it passes through the nozzle 19. This injection of the steam into the water not only heats the water but coöperates with the injector 13 to force the water through the heater.

It will be observed therefore that I have not only constructed the heater so that there is no possible waste of heat in the passage of steam therethrough, but I have also applied the steam exhausted from the heater for the purpose of raising the temperature of the water and also utilize the pressure of the escaping steam to assist in forcing the water through the heater.

What I claim is:

1. In a device of the class described, the combination of a heater provided therein with a passageway for steam and a passageway for water surrounding the steam passageway, and means for introducing the steam after passing through the steam passageway and having its pressure and temperature lowered into the water flowing to the water passageway anterior to its delivery to said passageway.

2. In a device of the class described, the combination of a heater provided therein with a passageway for steam and a passageway for water surrounding the steam passageway, an inlet to and an outlet from said water passageway, and means for introducing the steam after passing through the steam passageway and having its pressure and temperature lowered into the inlet anterior to its connection to the water passageway.

3. In a device of the class described, the combination of a heater provided therein

with a passageway for steam and a passageway for water surrounding the steam passageway, an inlet pipe leading to the water passageway and provided with a water delivery nozzle anterior to its connection to said passageway, a steam chamber surrounding said nozzle and an exhaust pipe from the steam passageway opening into said steam chamber.

4. In a device of the class described, the combination of a heater provided therein with a passageway for steam and a passageway for water surrounding the steam passageway, an inlet pipe and an outlet pipe at opposite ends of the water passageway, a reducing nozzle forming a part of the inlet pipe exterior to the heater and in advance of the inlet end of the water passageway for forcing water through the inlet pipe, a steam chamber encircling said nozzle and communicating with the inlet pipe, and an exhaust pipe from the steam passageway to said steam chamber.

5. In a device of the class described, the combination of a heater provided therein with a return passageway for steam, a passageway for water entirely surrounding the steam passageway to provide for an exchange of heat between the steam and water, an outlet pipe and an inlet pipe at opposite ends of the water passageway, and a pipe connecting the return end of the steam passageway to the water inlet pipe in advance of its connection to the water passageway.

6. In a device of the class described, the combination of a heater provided therein with a return passageway for steam, a passageway for water entirely surrounding the steam passageway to provide for an exchange of heat between the steam and water, an inlet pipe and an outlet pipe at opposite ends of the water passageway, a pipe connecting the return end of the steam passageway to the water inlet pipe in advance of its connection to the water passageway, and means in the inlet pipe at the point of connection with the steam pipe for forcing water into the heater and causing the steam of reduced temperature delivered thereto to commingle with the flowing water.

7. In a device of the class described, the combination of a heater provided therein with a tortuous passageway for steam having an inlet at one end and an outlet at its opposite end, a passageway for water entirely surrounding the steam passageway to provide for an exchange of heat between the steam and water, a water inlet pipe and a water outlet pipe at opposite ends of the water passageway, and a connection between the outlet end of the steam passageway and the water inlet pipe in advance of its opening into the water passageway to convey steam of reduced temperature to the entering water.

8. In a device of the class described, the combination of a heater provided therein with a relatively long steam passageway longitudinally divided to cause the steam to move from end to end and return, a passageway for water entirely surrounding the steam passageway, a water inlet pipe to and a water outlet pipe from said water passageway, and a pipe connecting the return end of 10 the steam passageway with the water inlet pipe in advance of its connection to the water passageway.
9. In a device of the class described, the combination of a heater provided therein 15 with a relatively long steam passageway comprising an outer tubular member closed at one end surrounding an inner tubular member opening into the outer tubular member near its closed end, a water passageway 20 encircling the steam passageway from end to end thereof, a water inlet pipe and a water outlet pipe at opposite ends of the water passageway, a steam outlet pipe extending from the outer tubular member of 25 the steam passageway to the water inlet pipe in advance of its connection to the water passageway to introduce steam of reduced temperature into the water entering
- the heater, and a steam inlet pipe connected to the inner tubular member of the steam 30 passageway.
10. In a device of the class described, the combination of a heater comprising a longitudinal casing, a steam passageway extending therethrough from end to end formed of 35 an outer tubular member with closed ends having a steam outlet through one end, and an inner parallel tubular member near the top of the outer member extending through one of the closed ends and terminating near 40 the other end, an annular water passageway entirely surrounding the steam passageway, a water inlet pipe and a water outlet for the water passageway, a steam inlet connected to the inner tubular member of the 45 steam passageway, and a steam outlet leading from the outer tubular member to the water inlet pipe and opening into the same in advance of its connection to the water 50 passageway.

In testimony whereof I have affixed my signature in presence of two witnesses.
